Inventor

Thomas Shaw

United States Patent Office.

THOMAS SHAW, OF PHILADELPHIA, PENNSYLVANIA.

Letters Patent No. 98,198, dated December 21, 1869.

IMPROVEMENT IN CARTRIDGE-FEEDERS FOR GUN-HAMMERS.

The Schedule referred to in these Letters Patent and making part of the same.

To all whom it may concern:

Be it known that I, THOMAS SHAW, of the city and county of Philadelphia, Pennsylvania, have invented a new and improved Method of Feeding Cartridges to the Cylinder of Shaw's Gunpowder-Hammer; and I hereby declare the following to be a full, clear, and exact description of the same, reference being had to the accompanying drawing, and to the letters of reference marked thereon.

My invention consists in the feeding of cartridges to the gun or cylinder of said gunpowder-hammer, by means of motion derived from the falling hammer, in the manner and for the purpose as hereafter described.

The object of the invention is to feed the cartridges rapidly.

In order to enable others to use and practise my invention, I will proceed to describe its construction and operation.

On reference to the accompanying drawing, which form part of the specification, the sketch represents a vertical section through the centre of the apparatus, of which *a* is the base, secured to which is the tube *b*, slotted throughout its length, to form guides for the reception of hammer *c* and cylinder or gun *d*. Said cylinder *d* is bored on its upper end, for the reception of plunger or lower end of hammer *c*.

The tube *f* is secured at its lower end, at *k*, to cylinder *d*, and is provided with a screw-cap, *m*, and is intended to contain a number of cartridges, *l*; and has a flat plunger, *o*, moving through a slot in lower end of tube *f*, said slot being equal in thickness to one of the cartridges, and said plunger *o* is thrust through

said slot, by means of lever *i*, having its fulcrum at *s*. The upper end of said lever *i* slides upon a cam, *g*, of hammer *c*, on the descent of said hammer *c*, which pushes a cartridge out of tube *f*, by means of plunger *o*, with sufficient force to throw the same into gun *e*, and on the entering of plunger *h* into the gun, the powder is exploded, (by virtue of the contraction of the air contained therein,) when the hammer is thrown violently upward, releasing the lever *i* from the cam *g*, permitting the spring *n* to force out plunger *o*, so as to allow the fall of another cartridge to the bottom of tube *f*, in front of plunger *o*, that it may be pushed out of the tube into the gun by the descent of the hammer, as before described.

The cap *m* is to enable the insertion of the cartridges in tube *f*, and a spiral spring can be employed to keep the cartridge down in place.

It will be observed that the tube *f* need not be in the precise location shown, and that the plunger *o* can be operated by levers and cam-rods in various positions, without any alteration in the result.

What I claim, and desire to secure by Letters Patent, is—

The combination of the cartridge-tube *f* with the cylinder *d*, plunger *o*, lever *i*, and cam *g*, operated in the manner substantially as and for the purpose set forth.

THOMAS SHAW. [L. S.]
